UNITED STATES PATENT OFFICE.

THOMAS KEELY, OF MEMPHIS, TENNESSEE.

WASTE-PIPE.

SPECIFICATION forming part of Letters Patent No. 444,297, dated January 6, 1891.

Application filed July 11, 1890. Serial No. 358,366. (No model.)

To all whom it may concern:

Be it known that I, THOMAS KEELY, of Memphis, in the county of Shelby and State of Tennessee, have invented a new and Improved Waste-Pipe, of which the following is a full, clear, and exact description.

My invention is an improvement in the class of waste-pipe attachments for refrigerators and other apparatus in which a drip-pipe projects downward into a waste-pipe proper, but is not arranged in contact with it.

My invention is embodied in the particular construction of the drip-pipe, as hereinafter described.

Reference is to be had to the accompanying drawings, forming a part of this specification, in which similar letters of reference indicate corresponding parts in all the figures.

Figure 1 is a front view of the improvement as applied to a refrigerator, which is shown in section. Fig. 2 is an enlarged transverse section of the improvement, and Fig. 3 is a front perspective view of the same.

The improved waste-pipe A, as shown in the drawings, is applied to a refrigerator B, but may also be equally well applied on other apparatus. The refrigerator B is provided with the usual receptacle C for containing the ice, and from which the drip-water is to be discharged through the waste-pipe to the outside.

In the bottom of the receptacle C opens a drip-pipe D, provided with an inwardly-bent end E, the point of which terminates in the center of the drip-pipe D. The lower end of this pipe D is cut out at the front at F, so that water passing down the inner walls of the said pipe accumulates on the point E to form a drop, which drops off the said point through the center of the waste-pipe A.

The drip-pipe D extends centrally into a vertically-arranged pipe G, somewhat larger in diameter and provided on its lower end with a reduced part H passing into the outlet in the bottom of the refrigerator B to the outside to discharge into the drip-pan I or other receptacle. In the upper part of the pipe G, opposite the cut-out part F, is ar-

ranged an elongated opening J, and a semi-circular opening K is arranged near the lower end of the said pipe G, so that air can readily pass through the pipe G, and at the same time the openings J and K permit of inserting a cleaning device into the pipe, so as to clean the lower end of the latter and drip-pipe D. The pipe G is arranged vertically, so that the water dripping off of the point E of the drip-pipe D falls through the pipe G without touching the walls of the latter, the drops landing directly in the pan I.

The waste and other impurities from the receptacle C pass through the drip-pipe D onto the point E of the latter, and then fall through the center of the pipe G, as previously described, so that the waste-pipe is prevented from soiling and fouling. The inwardly-curved point E of the drip-pipe can be readily cleaned from the outside through the opening J in the pipe G.

Having thus described my invention, what I claim as new, and desire to secure by Letters Patent, is—

1. The combination, with an outer pipe, of an inner drip-pipe provided with an inwardly-curved point terminating in the center line of the pipe, substantially as shown and described.

2. A waste-pipe comprising a vertically-arranged pipe and a drip-pipe extending into the upper end of the said vertical pipe and provided with an inwardly-curved lower end, the point of which is in line with the center line of the said vertical pipe, substantially as shown and described.

3. A waste-pipe comprising a vertically-arranged pipe having side openings near the top and bottom, and a drip-pipe extending in the said vertically-arranged pipe and provided with an inwardly-curved end, the point of which terminates in the center of the vertically-arranged pipe, substantially as shown and described.

THOMAS KEELY.
